CLAIM

The ornamental design for a cup lid, as shown and described.

DESCRIPTION

FIG. 1 is a perspective view of a cup lid showing my design;

FIG. 2 is a top plan view on a reduced scale;

FIG. 3 is a side elevational view, the opposite side being the same in appearance; and

FIG. 4 is a bottom plan view thereof.

FIG. 1

FIG. 2

FIG. 3

FIG. 4
